UNITED STATES PATENT OFFICE.

WILLIAM O. TAYLOR, OF LIMERICK, PENNSYLVANIA, ASSIGNOR TO WILDMAN MFG. CO.,
OF NORRISTOWN, PENNSYLVANIA, A CORPORATION OF PENNSYLVANIA.

STOP-MOTION.

1,254,086.

Specification of Letters Patent. Patented Jan. 22, 1918.

Application filed May 1, 1916. Serial No. 94,705.

To all whom it may concern:

Be it known that I, WILLIAM O. TAYLOR, a citizen of the United States, residing at Limerick, Pennsylvania, have invented certain new and useful Improvements in Stop-Motions, of which the following is a specification.

The invention consists in the features and combination and arrangement of parts hereinafter described and particularly pointed out in the claims.

In the accompanying drawings:

Figure 1 is a side view of the upper portion of a knitting head with my improvement in place.

Fig. 2 is a detail plan view of parts shown in Fig. 1.

I have shown the invention as applied to a machine of the rib type 1 being the dial post of such a machine, though I have not thought it necessary to show the needle dial, nor the needle cylinder. It will be understood however, that I do not restrict myself in the use of the invention to this type of machine, but it is merely illustrated and referred to as one instance of the use of the invention. A rotary bobbin stand is shown at 2 and a revolving yarn carrier at 3, these parts moving within a stationary frame ring 4. On a ring 5 revolving with the bobbin stand are pivotally mounted members 6, these being adapted to swing outwardly when free to do so, about their pivots 7 supported in brackets 8 carried by the revolving ring member 5. The members 6 which are subjected to the action of centrifugal force may be of various forms and may be arranged in a variety of ways but in the particular construction shown they are pivoted to swing radially of the machine and each of these members in the instance shown, comprises an upwardly extending portion, an outwardly extending head 6' and a foot portion 6''. When the yarn fails and allows the member 6 to swing outwardly under centrifugal force as will be presently described, the foot portion 6'' will swing down into the path of one of the projections 9 of a ring 10, which is supported on the fixed frame ring and as the member 6 is now in revolution about the axis of the knitting head, the contact of its foot 6'' with one of

the studs 9 will impart to the ring 10 a rotary movement with the result that one of the radial studs 11 will be brought against 55 the arm 12 and this arm will be moved to operate the let off mechanism.

When the machine is running with the yarns feeding properly the members 6, will be held in the position shown at the left 60 of Fig. 1 and in Fig. 2 by the draft of the yarn over a feeler finger or lever, which is connected with and holds the member 6 against outward movement, until such time that the yarn fails. This lever is shown at 65 13 and in the particular form shown which is an example of my invention this lever is pivotally mounted at 14 upon feeler 6, it being in the form of a wire arm, the intermediate portion of which is coiled or turned 70 about the pin at 14 to act as a pivot, the other arm 13' of the lever finding a fulcrum bearing against the side of a post or rod 15 extending up from one of the bearings or brackets 8. The yarn indicated at X comes 75 down from the overhead sweep or other guide passing through a guide eye at 16, and thence to the arm 13 of the lever over which it is bent on its way to the yarn guide eye 3. The draft of the yarn is substantially 80 at right angles to the arm 13 of the lever and the point at which this draft is applied to the lever is near the outer end thereof and preferably at the greatest distance possible from the fulcrum 15, it being observed 85 in this connection that the centrifugal member 6 connects with the feeler lever close to the fulcrum 15 thereof, so that comparatively slight draft of the yarn on the feeler finger or lever will maintain this in the 90 normal position shown in Fig. 2 and against the tendency of the member 6 to fly outwardly under centrifugal force. In other words a slight draft, or the draft of tender yarn, will be sufficient to hold the centrifugal 95 member 6 against action owing to the relation of the fulcrum 15 to the point of connection with the member 6 and the length of the arm 13 to the point where the draft of the yarn is applied to feeler lever. Now as 100 soon as the yarn breaks or drops off and the feeler lever or finger 13, 13' is relieved from restraint of the draft of the yarn the member 6 will immediately fly out radially.

under the action of centrifugal force and will cause its foot portion 6^x to contact with a stud 9 and rotate the ring 10 and through one of the projections 11 of the ring the 5 arm 12 will be operated to stop the machine.

I prefer to form the arm or feeler finger 13, 13' with a fork or loop to embrace the fulcrum 15, so that in resetting the centrifugal member 6 the feeler finger will be automatically reset or conversely by exerting pressure of the finger or hand upon the portion 13' of the feeler finger to reset it the same act will reset the pivoted member 6. I also prefer to form the feeler finger 13, 15 together with its extension 13' of wire, this being inexpensive and effective. I provide the feeler finger with a hooked end 13^x to retain the yarn in engagement therewith. I have shown the member 6 as movable in a 20 vertical radial plane, and the feeler finger movable in substantially a horizontal plane but other dispositions of these parts may be used to accomplish the results desired within the purview of my invention.

25 It will be observed that when the arm 6 is in normal position, as shown on the left of Fig. 1, the preponderance or substantially all of its weight is exerted to hold or tend to hold the member in the position shown 30 and this, together with the draft of the yarn on the feeler finger and the leverage action of said feeler finger will serve to retain the weight member 6 in said normal position until upon the failure of the yarn the restraint 35 exerted by the feeler finger lever will be removed and centrifugal force will then overcome gravitation and the member 6 will fly out and operate the let-off connections.

An adjustable weight may be employed as 40 at 17 mounted to be raised or lowered and this renders the member 6 more or less sensitive to the action of centrifugal force but the adjustment of the weight does not alter the force of gravity acting on the movable member, said weight being adjustable vertically. Any suitable stop may be employed to limit 45 the inward movement of the weighted member 6.

The stop motion is adapted for use with 50 any desired number of feeds. I prefer to have all of the members 6 act through the element 10 common to them all in actuating the let-off connections. The stop motion devices described may be associated with any 55 desired form of overhead sweep, and with knot catcher devices so that should the yarn be caught at the bobbin and fail to feed or should a knot tangle, or bunch occur the let-off will be operated.

60 The apparatus is self compensating in that when the speed changes the centrifugal force changes and also the draft of the yarn changes, so that a compensating effect is secured.

65 It will be observed that as the weighted

arm swings outwardly under centrifugal force the leverage exerted by the feeler finger is decreased, because as the feeler lever turns the yarn approaches and slides closer to the fulcrum point. Furthermore, when 70 the weighted arms move outwardly the attraction of gravity becomes less effective, because of the arm moving over its center and then there will be less resistance to the centrifugal force and as a result of the reduced 75 leverage and reduced gravitation it will be clear that when the pivoted arm 6 is once started, its action is quick or is accelerated by reducing or removing the opposing factors or forces. 80

The relation of the yarn guide openings to the lever is such that when the parts are in normal position, as shown in Fig. 2, the yarn will extend at practically a right angle to the lever or arm. 85

This stop motion will operate as well when the yarn breaks at the needles *i. e.* between the stop motion device and the fabric, as when it breaks above the stop motion device because the operation depends upon the cessation of the draft of the yarn on the yarn lever. 90

The invention may be used in connection with a single feed machine having two threads, which would be laid over the same 95 feeler lever, so that the aggregate drag of these two yarns would be sufficient to hold the feeler lever in normal position. Each yarn would have its own sweep or cast off hook and if either one failed the reduction in 100 or removal of its drag would be such that the centrifugal force would then be sufficient to operate the weighted arm or lever.

Other forms of weighted members may be used in place of the levers. 105

The ring 4 is held against rotative movement by any suitable part extending up from the fixed main frame.

In order to meet varying conditions affecting control of the centrifugal member 110 of the stop motion, such as increased or diminished yarn draft due to running a lighter or heavier gage or to the material or nature of the yarn, and also the variations in speed affecting the amount of centrifugal force 115 to be controlled, I make the plate 16^a or bobbin stand carrying the guide eyes 16 adjustable about its axis so that such adjustment, by changing the angle at which the yarn leads over the feeler fingers 13 will cause 120 the length of lever on which the yarn acts to be changed and restrain movement of the centrifugal member to a greater or lesser degree as may be required.

I prefer to accomplish the result aimed 125 at in this way rather than by an adjustment that would affect the relative positions of pivot 14 and fulcrum 15, on account of the greater ease with which simultaneous adjustment on all or a number of 130

the stop motion units can be accomplished, though the change of leverage desired could be secured in either of the two ways.

In Fig. 1, I show at 18 a form of adjustment which is representative of any that may be employed for the purpose, this consisting of screws (only one being shown) passing through a slot 16' in the plate and into the stand 2.

10 Fig. 2 indicates at 16^a in dotted lines the position to which the guide eye 16 may be adjusted by turning the plate 16^a.

Where it is desired to do plating a pair 15 of the stop motion units may be employed and these will be set adjacent each other but in reversed position.

Fig. 2 indicates at 13^a the feeler lever of the adjacent unit which co-operates with the feeler lever 13 for guiding the yarn 20 which, together with the yarn guided by the finger 13, is to do plating. In such a case the guide eyes for the respective feelers or units would be adjusted in opposite directions because of the reversed position of the 25 feeler levers.

What I claim is:—

1. In a stop motion for knitting machines the combination of a member movable under the influence of centrifugal force in revolving 30 with the rotary parts of the machine, let-off connections operated thereby, and a feeler finger engaging and held by the yarn and thereby opposing the movement of said member under said force, the failure of the 35 yarn removing said member from the holding influence of said feeler finger, substantially as described.

2. In combination in a stop motion for knitting machines, a member revolving with 40 the rotating parts of the machine and movable under the influence of centrifugal force, let-off connections operated thereby and a feeler finger in the form of a lever, to which force is applied by the draft of the yarn 45 in engagement therewith to hold the said member against said centrifugal force so long as the normal draft of the yarn is maintained.

3. In combination in a stop motion for 50 knitting machines, a member revolving with the machine and movable under the influence of centrifugal force, let-off connections operated thereby and a feeler finger in the form of a lever to the longer arm of which force 55 is applied by the draft of the yarn and the short arm of which restrains the said member against movement, so long as the normal draft of the yarn on the lever is maintained, substantially as described.

60 4. In combination in a stop motion for knitting machines, a member revolving with the machine and movable under the influence of centrifugal force, let-off connections operated thereby and a feeler finger in 65 the form of a lever of the second order,

that is, with the said centrifugal member connected thereto at a point nearer the fulcrum than the point where the draft of the yarn is applied to said lever, to hold the member against movement so long as the 70 proper yarn feed is maintained.

5. In combination in a stop motion for knitting machines, a pivotal member revolving with the machine and adapted to move radially outward under centrifugal force, 75 and a feeler finger engaging said pivotal member, said feeler finger being held in position by the draft of the yarn to retain the said pivoted member against action until the yarn fails, substantially as described. 80

6. In combination in a stop motion for knitting machines, a pivoted member revolving with the machine and adapted to move outwardly under centrifugal force, and a feeler finger in the form of a lever fulcrumed 85 on the machine and engaging said pivotally mounted member, said feeler finger being held in position by the draft of the yarn to retain the said pivoted member against action until the yarn fails, substantially as 90 described.

7. In combination in a stop motion for knitting machines, a pivoted member revolving with the machine and adapted to move outwardly under centrifugal force, and 95 a feeler finger in the form of a lever fulcrumed on the machine and pivotally connected with said member nearer the lever's fulcrum than the point where the draft of the yarn is applied to said lever to hold it 100 and retain said member against centrifugal force, substantially as described.

8. In a stop motion for knitting machines and in combination a member revolving with the rotary parts of the machine and pivotally mounted to swing in a substantially vertical and radial plane under centrifugal force and a feeler finger in the form of a lever pivoted to the upper part of said member and a fulcrum for said lever, said feeler 110 finger restraining said member under the draft of the yarn and until the yarn fails, substantially as described.

9. In combination in a stop motion for knitting machines, a member pivotally 115 mounted to swing in a vertical plane the preponderance of weight of said member when in normal position being toward the inside of the pivot thereof and nearest to the axis of the machine and a feeler finger to engage the thread pivotally mounted on said member and a fulcrum for the feeler finger, 120 substantially as described.

10. In combination in a stop motion for a 125 knitting machine a member pivotally mounted and normally held toward the center of the machine and a feeler finger pivotally connected to said member and having a forked portion and a fulcrum engaging said forked portion, substantially as described. 130

11. In combination in a stop motion for a knitting machine, a member pivotally mounted, an adjustable weight carried by said member and holding the same normally 5 toward the center of the machine, said member being adapted to move outwardly from said normal position under the action of centrifugal force and a feeler finger pivotally connected with said lever, substantially 10 as described.
12. In combination in a stop motion for knitting machines, a member revolving with the machine about a vertical axis, said member being mounted on a pivot constantly 15 maintained in a horizontal plane to swing outwardly in a radial plane under centrifugal force while the machine is in motion, and gravitating toward the center of the machine when at rest, said pivoted member 20 at all of its angular positions about the said vertical axis responding uniformly to either of said forces, said member being additionally restrained against outward movement by the yarn, and a let-off connection 25 operated by said member when moved out by centrifugal force.
13. In combination in a stop motion for circular knitting machines, a member rotating with the machine and movable under 30 centrifugal force, a feeler finger connected with said member and subjected to the drag of the yarn to restrain the said member against movement, said feeler finger exerting a lever action upon said member, and 35 means of adjustment to render the drag of the yarn more or less effective in operating said feeler finger to restrain the movement of the member, substantially as described.
14. In combination in a stop motion for 40 circular knitting machines, a member revolving with the machine and movable under centrifugal force, a feeler finger subjected to the draft of the yarn and exerting a restraining influence on the said member, a 45 yarn guide directing the yarn to the feeler finger, said yarn guide being adjustable to change the point of application of said draft on the feeler finger to vary the restraining effect of the feeler finger on said member, 50 and let off connections controlled by the said member, substantially as described.
15. In combination in a stop motion for circular knitting machines, a plurality of members revolving with the machine and 55 movable under centrifugal force, a feeler finger connected with each member and subjected to the draft of the yarn individual thereto, said feeler fingers exerting a restraint on the members against movement 60 and a plurality of yarn guides adjustable simultaneously to vary the points of contact of the yarns with the feeler fingers to vary their restraining power on the members and let off connections controlled by the said 65 members, substantially as described.
16. In combination in a stop motion for circular knitting machines, a plurality of members revolving with the machine and movable under centrifugal force, a feeler finger connected with each member and subjected 70 to the draft of the yarn individual thereto, said feeler fingers exerting a restraint on the members against movement and a plurality of yarn guides mounted upon an adjustable plate and thereby adjustable 75 simultaneously to vary the points of contact of the yarns with the feeler fingers to vary their restraining power on the members and let off connections controlled by the said members, substantially as described. 80
17. In combination in a stop motion for circular knitting machines, a pair of members revolving with the machine and movable under centrifugal force, a feeler finger connected with each member and subjected 85 to the draft of the yarn individual thereto, said feeler fingers exerting a restraint on the members against movement, and extending in opposite directions with their yarn receiving ends adjacent for plating, substantially as described. 90
18. In combination in a stop motion for knitting machines, a let off connection, a member pivotally mounted to swing in a vertical plane and movable under stress to 95 throw the same into engagement with said let off connection to render the same effective in stopping the machine, and a feeler finger subjected to the draft of the yarn and resisting the movement of the said member 100 under said stress as long as the draft of the yarn is maintained, said feeler finger being in the form of a lever pivoted to said pivotally mounted member and turning about a fixed fulcrum, substantially as described. 105
19. In combination in a stop motion for knitting machines, a let off connection, a member pivotally mounted to swing in a vertical plane and movable under stress to 110 throw the same into engagement with said let off connection to render the same effective in stopping the machine, and a feeler finger subjected to the draft of the yarn and resisting the movement of the said member under said stress as long as the draft of the 115 yarn is maintained, said feeler finger being in the form of a lever pivoted to said pivotally mounted member and turning about a fixed fulcrum, the longer arm of said lever being engaged by the yarn, substantially as 120 described.
20. In combination in a stop motion for knitting machines, a let off connection, a member movable under stress to throw the same into engagement with said let off connection to render the same effective in stopping the machine, and a feeler finger subjected to the draft of the yarn and resisting the movement of the said member under 125 said stress as long as the draft of the 130 yarn

is maintained, said member being pivotally mounted to swing under said stress and the feeler finger being pivoted thereto and turning about a fixed fulcrum, substantially as described.

21. In combination in a stop motion for knitting machines, a member pivotally mounted and being under stress to swing it in a vertical plane and a yarn controlled 10 feeler finger in the form of a lever pivotally mounted at the upper part of said member and turning about a fixed fulcrum, and a let off connection controlled by the pivotally mounted member, substantially as described.

22. In combination in a stop motion for knitting machines, a member pivotally mounted and being under stress to swing it in a vertical plane and a yarn controlled feeler finger in the form of a lever pivotally 15 mounted at the upper part of said member and turning about a fixed fulcrum, and a let off connection controlled by the pivotally mounted member, said feeler finger turning in a substantially horizontal plane, substantially as described.

23. In combination in a stop motion for

knitting machines, a member pivotally mounted and being under stress to swing it in a vertical plane and a yarn controlled 30 feeler finger in the form of a lever pivotally mounted at the upper part of said member and turning about a fixed fulcrum, and a let off connection controlled by the pivotally mounted member, said lever having a slot to receive said fulcrum allowing the lever to 35 turn and slide on the fulcrum, substantially as described.

24. In combination in a stop motion for knitting machines, a member pivotally mounted to swing in a vertical plane, a 40 feeler finger subjected to the draft of the yarn and pivoted intermediate of its length to the top of the said vertically disposed member, a fixed fulcrum for the said finger located adjacent the vertically disposed 45 member, the yarn engaging arm of said feeler being longer than and on the opposite side of the pivot from that portion which engages the fulcrum.

In testimony whereof, I affix my signature.

WILLIAM O. TAYLOR.
